DISPLAY AND DISPENSING PACKAGE
FOR TABLETSArthur G. Sherman, Detroit, Mich., assignor to
Sherman Laboratories, Detroit, Mich., a partnership of Michigan

Application July 5, 1943, Serial No. 493,611

4 Claims. (Cl. 206—42)

1

This invention relates to display packages for tablets and the like and particularly packages designed for convenient withdrawal of one or a desired number of tablets.

An object of the invention is to provide a simpler and less expensive package than has heretofore been available for receiving, displaying, and individually dispensing tablets or similar products.

Another object is to provide a package comprising a sleeve-type wrapper of paper or the like, enclosing a member of cardboard or the like and having perforations for individually receiving tablets or like products, and to mount a transparent slide between the cardboard member and one side of the wrapper to normally close a window opening in the wrapper and cover said perforations, actuation of the slide serving to progressively open said window and uncover said perforations so that the tablets may be withdrawn through said opening.

A further object is to utilize said slide to shear a sticker or the like which initially retains the slide in proper position within the package.

A further object is to dispose two or more similar tablet-receiving, perforated members within the same wrapper, and to provide transparent slides for successive use in withdrawing the contents of said members.

These and various other objects are attained by the construction hereinafter described and illustrated in the accompanying drawing, wherein:

Fig. 1 is a top view of a tablet package illustrating one embodiment of the invention.

Fig. 2 is a similar view showing the transparent slide shifted to a position for permitting withdrawal of a single tablet.

Fig. 3 is a cross sectional view of the same, taken on the line 3—3 of Fig. 1.

Fig. 4 is a fragmentary section taken on the line 4—4 of Fig. 1.

Fig. 5 is a longitudinal sectional view of a modified form of the package.

Fig. 6 is a cross sectional view of such modified form, taken on the line 6—6 of Fig. 5.

Describing now in greater detail the invention as illustrated in Figs. 1—4, the reference character 1 designates an elongated rectangular member formed preferably of heavy cardboard and with two rows of perforations 2, each proportioned to freely receive a tablet 3. For reasons which will presently appear, it is preferred to relatively stagger the perforations in the two rows. Enclosing said member is a paper wrapper 4, preferably of a sleeve form, the bottom section

2

of such wrapper being adhesively or otherwise secured to the member 1. The top section of the wrapper has a window opening 5 or is otherwise apertured to register with all of the perforations 2, the ends of said opening preferably having an inclination to the wrapper ends determined by the staggered relation of the perforations. Between the member 1 and the top section of the wrapper is fitted a slide 6 formed of any suitable thin transparent sheet material having considerable stiffness, and said sheet may be withdrawn from the wrapper through either open end of the latter. To facilitate such withdrawal, the slide may have lugs 7 at its ends projecting beyond the wrapper when the slide is therein. Actuation of the slide exposes the tablets successively, due to staggered relation of the two rows, and at the same time sufficiently uncovers the opening 5 to permit withdrawal of any exposed tablet. It is preferred to assure against any accidental shifting of the slide prior to dispensing use of same, by attaching stickers 8 to the ends of the wrapper so as to partially close said ends, and the slide serves as a means for severing either of said stickers. In order that such severing may be progressive and thus be effected with slight effort, the ends 9 of the slide have a slight divergency to the ends of the wrapper.

30 It is evident that the described construction is quite inexpensive, due to its extreme simplicity and the very common materials employed. Its use is, of course, not limited to tablets, although it is particularly adapted to such use.

35 It is important to note that the bottom section of the wrapper serves as a closure for the bottom ends of the perforations 2 while the opening of the top member of the wrapper permits the contents of the package to be seen and further provides an outlet for such contents. Inserting the slide between the member 1 and the top member of the wrapper provides for retaining and guiding the slide with a maximum of simplicity. Adaptability of the slide to be withdrawn from either end of the package adds materially to convenience of its use.

40 In the modification shown by Figs. 5 and 6, there are provided two elongated rectangular cardboard members 10 disposed one above the other, said members being each perforated at 11 to receive tablets or the like as in the first-described package. A single paper wrapper 12 encloses both members 10, the bottom section of said wrapper being adhesively secured to the 45 lower member 10 and the sides of the wrapper 55

being adhesively secured to the upper of said members. The top section of the wrapper has a window opening 13 such as previously described and between said section and the top member is inserted a transparent slide 14 functioning as in the first-described package. Additionally there is provided a transparent slide 15 between the members 10, both slides being held in proper place prior to their dispensing use by stickers 16 at the ends of the package. These stickers differ from those of the first-described construction in that they are adhesively secured to the end faces of the members 10 as well as to the wrappers, being thus adapted to hold the slide 15 in place, during use of the slide 14.

In use of this construction, the tablets carried by the lower member 10 are not disturbed until the upper member 10 has fully discharged its contents. The lower slide may then be discarded, and the slide 14 is actuated when desired to regulate discharge of tablets from the lower member 10. If a package of still greater capacity is desired, it is obvious that the number of perforated members and of corresponding slides may be still further increased, while still employing a single wrapper.

What I claim is:

1. A display package comprising a plurality of members formed of sheet material arranged side by side and having perforations, registered in the several members, for receiving products, a flexible wrapper extended around said members and having at least one of its ends open, one side of said wrapper closing the perforations of the member adjacent such side, and the opposite side of the wrapper being apertured to afford display of the products in the perforations of the adjacent member and to afford removal of the products from all of said members, a transparent slide fitted between the apertured side of the wrapper and the adjacent perforated member to normally retain the products in such adjacent member, and a slide interposed between each two adjacent members to normally retain the products in one of such members.

2. In a display package as set forth in claim 1,

sealing means for the open end of the wrapper adapted to be consecutively severed by the several slides.

3. A display package comprising a plurality of members formed of sheet material arranged side by side and having perforations, registered in the several members, for receiving products, a flexible wrapper extended around said members and having at least one of its ends open, one side of said wrapper closing the perforations of the member adjacent such side, and the opposite side of the wrapper being apertured to afford display of the products in the perforations of the adjacent member and to afford removal of the products from all of said members, a transparent slide fitted between the apertured side of the wrapper and the adjacent perforated member to normally retain the products in such adjacent member, a slide interposed between each two adjacent members to normally retain the products in one of such members, a sealing element adhesively secured at the open end of the wrapper to the ends of the perforated members, and adapted to be severed by the several slides.

4. A display package comprising a filler forming a plurality of similar cells for receiving products, a flexible wrapper extended around said filler and having at least one of its ends open, one side of said wrapper closing said cells and the opposite side of the wrapper being apertured to afford display and discharge of said products, an adhesive securing said filler to and retaining it in the wrapper, a transparent slide fitted between the filler and apertured side of the wrapper to normally retain said products in said cells, and adapted to be withdrawn through said open end of the wrapper to progressively uncover the cells and afford discharge of said products, and sealing means for the end of the wrapper through which the slide is to be withdrawn, the slide having an edge for severing said sealing means, such edge being so divergent to the sealed end of the wrapper as to be progressively subjected to the stress incident to shearing of the seal.
